UNITED STATES PATENT OFFICE.

WARREN M. BRINKERHOFF, OF AUBURN, NEW YORK.

DESIGN FOR A FIRE-POT.

SPECIFICATION forming part of Design No. 33,521, dated November 6, 1900.

Application filed October 2, 1900. Serial No. 31,789. Term of patent 14 years.

To all whom it may concern:

Be it known that I, WARREN M. BRINKERHOFF, a citizen of the United States, residing at Auburn, in the county of Cayuga and State 5 of New York, have invented and produced a new and original Design for a Fire-Pot; and I do hereby declare the following to be a full, clear, and exact description of the same, reference being had to the accompanying drawings, forming a part thereof.

In the drawings, Figure 1 is a plan view or a top view of a fire-pot embodying my design. Fig. 2 is a vertical section on line 2 2 of Fig. 1.

A indicates the body of the fire-pot, which 15 is of circular form. At two or more places on its top it is provided with the outwardly-extending projections a' a'. The top of these

projecting portions is raised vertically, forming upwardly-extending projections of an upwardly-curved form, as most clearly shown 20 by dotted lines in Fig. 2.

The essential or characteristic feature of the design is the circular body, with the outwardly and upwardly extending projections.

What I claim, and desire to secure by Letters Patent, is—

The design for a fire-pot as described and shown.

In testimony whereof I affix my signature in presence of two witnesses.

WARREN M. BRINKERHOFF.
